WARE

INDEX TAB FOR RECORD GUIDES

Application filed January 9, 1929. Serial No. 331,197.

- This invention relates to a record guide. More particularly, it relates to an index tab formed on a record guide.
- In various filing systems guides are disposed throughout the mass of filing elements or records. These guides are usually provided with tabs to identify and index the various records. In most of the guides used prior to this invention the tabs were affixed to the body of the guide by an adhesive, rivets or other means. This produced a guide which had several disadvantages. Due to the method of attaching the index tab to the guide body an increased thickness was abruptly produced at a portion of the surface of the guide which came in contact with the filed records, whereby the entire file was caused to assume a fan-like shape, that is, it was wider at the top than at the bottom. It was thus impossible to obtain an equal pressure over the entire surface of the filed records to "iron" the same when not in use. This unequal pressure would cause a wrinkling of the typed data thereon and possible obliteration or smudging of the filed matter adjacent the abrupt change in the file guide surface.
- I have found that I can eliminate the above described disadvantages by forming or providing an index tab on a record guide which terminates at its lower edge above the upper edge of the body member of the guide whereby when in use it lies outside the general outline of said guide.
- It is, therefore, an object of this invention to provide a record guide having an index tab so constructed that it will not produce a fan-like effect in use.
- Another object of this invention is to provide a record guide having a double-faced index tab so disposed that it will not engage the records in the filing system.
- A specific object of this invention is to provide a record guide comprising a body member having a tab extending therefrom, said tab having a plurality of apertures therein, a clip having a plurality of projections registering with said apertures and disposed on said tab and a transparent sheath disposed on said clip and cooperating there-
- with to form pockets to receive index cards, inserts and the like.
- Other objects will appear from the following description, appended claims and accompanying drawings in which:
- Figure 1 is a front view of a central portion of a record guide including the index tab constituting this invention.
- Figure 2 is a sectional view taken on lines 2-2 of Figure 1, showing the insert in position.
- Referring to the drawings wherein like reference numerals designate like parts, the reference numeral 1 designates a body member having a projection or tab 2 extending therefrom. The body member 1 may be made of any desired shape, size or material. I prefer, however, to make it rectangular in shape. Various materials may be used for the manufacture of this guide. I prefer to make it of metallic material such as aluminum. The tab 2, as above stated, extends from the body member 1. In the drawings wherein a central portion of the record guide is illustrated the tab is positioned in the center of the record guide. It is to be understood, however, that it may be positioned wherever desired.
- The tab 2 is provided with apertures 3 which are adapted to receive projections 4 of a clip member 5, whereby said clip member is secured or locked to the tab. The clip member 5 is made of a resilient material such as tin plate, spring steel or the like, formed in the shape of an inverted U. For reasons which will become apparent the portion between the legs 5' of the clip 5 may be rounded or beaded out as indicated at 6.
- As previously stated, the clip 5 is provided with projections 4 in one of its legs 5'. These projections may be of any desired type. I have found that I can obtain satisfactory results if the projections are made in the form of sprung-back tongues as illustrated.
- Disposed on the clip 5 is a U-shaped sheath 7 formed of a colored or uncolored transparent material such as celluloid or the like. This sheath 7 is provided with inturned edges 8 into which the ends of the legs of the clip 5 extend. The legs of the clip and the trans-

parent member cooperate with each other to form pockets 9 adapted to receive the index cards or inserts 9'. By making the curved portion 7' of the sheath 7 engage the beaded portion 6 of the clip 5, close tolerances and substantially uniform pockets may be obtained. It is to be noted that the pockets are formed on both sides of the index tab 2. This permits the reading of the indices from 10 both sides.

As above stated, one of the essential objects of this invention is to provide a record guide with an index tab to eliminate the fan-like effect when used in the filing system. To attain this object the clip 5 and its cooperating sheath 7 are made to terminate at its lower edge above the edge of the body member indicated by the reference numeral 10. By this arrangement all parts of the index tab when 15 in use lie above the filed records and do not contact therewith, thus permitting the filed records and the record guides to be flush with each other. Besides eliminating the undesirable fan-like effect, the record guides exert 20 an equal pressure on the filed records thus "ironing out" said records when not in use. Due to the disposition of the index tab above 25 the body member, the tendency to smudge is eliminated.

In use, due to inclining and flexing of the guide, a record may be caught and held between the tab 2 and the sheath 8. To prevent this, means are provided which will deflect the record outwardly when engaged by the 30 record guide adjacent the lower extremity of the tab. This means may comprise various constructions. In the drawings the projections 11 formed by depressing or offsetting certain portions of the tab illustrate 35 one. These projections are disposed on both sides of the tab in the portion of the tab 2 above the body member 1 and below the sheath 8. Any desired number may be used. I have obtained satisfactory results with two 40 on each side, those on one side being staggered with respect to those on the other. Instead of the deflecting means above described, a strip of material of triangular cross-section having its thin edge adjacent the body member and secured to the tab in any suitable 45 manner may be used.

Instead of forming the tongues and apertures in the clip and tab respectively as above described, the tongues or other projections 50 may be formed in the tab and the apertures in the clip. Also, if desired, the ends of the clip may be bent outwardly in a horizontal direction and form a support for the inserts.

The index clip produced as above described is substantially rigidly secured to the tab. It can only be removed by inserting an instrument, such as a knife blade, between the 55 clip and the tab and spreading said clip suffi-

ciently to permit the projecting portions to release themselves from the apertures.

Since it is obvious that various modifications may be made in the specific details above described without departing from the 70 nature of the invention, this application is not restricted to said specific details except as defined in the appended claims.

I claim:

1. A record guide comprising a body member having a tab extending therefrom, a clip secured to said tab, and a transparent sheath disposed on said clip and cooperating therewith to form pockets to receive index cards or inserts, said clip and sheath lying outside 80 the general outline of said body member.

2. A record guide comprising a body member having a tab extending therefrom, said tab having a plurality of apertures therein, a U-shaped clip disposed on said tab and having projections registering with said apertures, and a transparent sheath disposed on 85 said clip and cooperating therewith to form pockets to receive index cards or inserts.

3. A record guide comprising a body member having a tab extending therefrom, said tab having a plurality of apertures therein, a U-shaped clip disposed on said tab and having projections registering with said apertures, and a U-shaped transparent sheath disposed on said clip and cooperating therewith 90 to form pockets to receive index cards or inserts.

4. A record guide comprising a body member having a tab extending therefrom, said tab having a plurality of apertures therein, a U-shaped clip disposed on said tab and having projections registering with said apertures, and a U-shaped transparent sheath disposed on said clip and cooperating therewith 100 to form pockets to receive index cards or inserts, said sheath having upturned ends receiving the ends of said clip.

5. A record guide comprising a body member having a tab extending therefrom, said tab having a plurality of apertures therein, a U-shaped clip disposed on said tab, said clip having a beaded portion and a plurality of projections registering with said apertures, and a transparent U-shaped sheath disposed 110 on said clip and cooperating therewith to form pockets to receive index cards or inserts.

6. A record guide comprising a body member having a tab extending therefrom, said tab having a plurality of apertures therein, a U-shaped clip disposed on said tab, said clip having a beaded portion and a plurality of projections registering with said apertures, and a transparent U-shaped sheath disposed 120 on said clip and cooperating therewith to form pockets to receive index cards or inserts, said sheath having upturned ends receiving the ends of said clip.

7. A record guide comprising a body mem-

ber having a tab extending therefrom, said tab having a plurality of apertures therein, a U-shaped clip disposed on said tab and having projections registering with said apertures, and a transparent sheath disposed on said clip and cooperating therewith to form pockets to receive index cards or inserts, said clip and sheath lying outside the general outline of said body member.

In testimony whereof, I have affixed my

8. A record guide comprising a body member having a tab extending therefrom, said tab having a plurality of apertures therein, a U-shaped clip disposed on said tab and having projections registering with said apertures, and a U-shaped transparent sheath disposed on said clip and cooperating therewith to form pockets to receive index cards or inserts, said clip and sheath lying outside the general outline of said body member.

signature to this specification. **ELMER W. DAVIS.**

20 9. A record guide comprising a body member having a tab extending therefrom, said tab having a plurality of apertures therein, a U-shaped clip disposed on said tab and having projections registering with said apertures, and a U-shaped transparent sheath disposed on said clip and cooperating therewith to form pockets to receive index cards or inserts, said sheath having upturned ends receiving the ends of said clip, said clip and sheath lying outside the general outline of said body member. 85
